Primary Examiner — Garth Rademaker(74) *Attorney, Agent, or Firm* — Gardner, Linn, Burkhart & Flory, LLP(57) **CLAIM**

The ornamental design for a garden plant support, as shown and described.

DESCRIPTION

FIG. 1 is a perspective view of a garden plant support in accordance with the present invention, shown in use between a pair of supports;

FIG. 2 is a perspective view of the garden plant support of FIG. 1;

FIG. 3 is a side elevation of the garden plant support of FIGS. 1 and 2;

FIG. 4 is an opposite side elevation of the garden plant support of FIGS. 1 and 2;

FIG. 5 is an end elevation of the garden plant support of FIGS. 1 and 2;

FIG. 6 is an opposite end elevation of the garden plant support of FIGS. 1 and 2;

FIG. 7 is a top plan view of the garden plant support of FIGS. 1 and 2; and,

FIG. 8 is a bottom plan view of the garden plant support of FIGS. 1 and 2.

The broken lines in FIG. 1 depict environmental subject matter only and form no part of the claimed design.
